STEAM GENERATING APPARATUS

Arthur E. Duram, Springfield, Ill., assignor to
 Springfield Boiler Company, Springfield, Ill., a
 corporation of Illinois

Application October 10, 1934, Serial No. 747,764

7 Claims. (Cl. 122—235)

This invention relates to steam generating apparatus and particularly to apparatus of this kind of relatively large size and high steam generating capacity. Certain features of the invention are directed to the water walls of the furnace which are intended to reduce the temperature of the furnace in order to keep the same below the fusing temperature of the slag or non-combustible ingredients of the fuel which is being burned in the furnace.

Heretofore in furnaces of this type it has been standard practice to water cool the rear and side walls, and in cases of high heat release, the front wall, which has operated in a reasonably satisfactory manner up to a furnace width of approximately fifteen feet. In furnaces of greater width than this where two or more burners are employed to generate the necessary steam requirements, it has been found that the radiant absorption to the outside wall cooling tubes has been reasonably satisfactory to reduce the temperature of the rising ash particles below a plastic temperature in the portions of the furnace adjacent to such outer walls. However, in the center of the furnace between the burners where the burning fuel has a tendency to cloud the radiant effect of such outer wall tubes it has been found that the furnace temperature rises to a considerable extent above the balance of the furnace, creating a plastic condition of the ash which accumulates rapidly upon the lower tube bank of the boiler, diminishing the gas passages to such an extent as to prohibit normal operation. In order to reduce this higher temperature in the center of the furnace attempts have been made to install single rows of vertical water tubes between the burner zones. In such conditions it has been found that due to the excessive radiant heat absorbed from both sides of the single row of tubes, the evaporation in such vertical rows has been extremely excessive even to the point of lowering the water content in the tubes to such an extent as to overheat the tubes and cause failure. In order to overcome such a condition I propose to install a double row of tubes in such formation as to cause one row to shield the other from the radiant heat of the opposite zone and thereby create an operating condition having a degree of radiant absorption in the center or partition wall more nearly to that of the outside wall and reduce the possibility of excessive generation in the tubes of the center or partition wall.

The objects of this invention as above indicated are to provide an improved steam generat-

ing apparatus; to provide a relatively large furnace for a boiler, with one or more partition walls each formed of a plurality of rows of vertical water tubes; to provide an apparatus of this character having means for access to various portions thereof for construction, inspection and cleaning purposes; and to provide such other improvements in construction and advantages in operation as will appear more fully from the following description.

In the accompanying drawings illustrating this invention,

Figure 1 is a vertical sectional view taken approximately on the line 4—4 of Figure 4;

Figure 2 is a detail of one of the headers with pipes connected therewith;

Figure 3 is a detail of the center wall supporting means; and

Figure 4 is a vertical sectional view taken on the line 4—4 of Figure 1.

It will be understood that in these drawings parts are shown diagrammatically and other parts may be omitted, sufficient being illustrated so that the invention will be readily understood by those familiar with the art.

As shown particularly in Figure 1, the furnace or combustion chamber 5 is shown with a rear water wall 6 and side water walls 7 and 8 and if desired may be provided with a front water wall, which however is not shown, this being more or less standard construction. The tubes of the rear water wall are connected at the top with a header 9 and at the bottom with a header 10. The header 9 is connected to the boiler drum 11 in any suitable or well-known manner as by means of risers 12. The return from the drum 11 to the lower header 10 may also be arranged in any desired manner, as for instance in the arrangement shown, a transverse header 13 is connected to the drum by means of a plurality of pipes 14. Downcomer or return pipes 15 extend downwardly from the ends of the header 13 and are connected to the header 10 by a plurality of pipes 16 as shown.

The tubes of the water wall 7 are connected at the top with a header 17 and at the bottom with a header 18 and the tubes of the water wall 8 are connected in a similar manner at the top with a header 19 and at the bottom with a header 20. The headers 17 and 19 may be connected with the drum 11 in any standard or well-known manner as by means of pipes 21 and 22. The headers 18 and 20 are connected respectively with the return pipes 15 by means of pipes 23 and 24 which enter the ends of short headers 25 which

are directly connected to the lower ends of the pipes 15 as shown in Figure 4.

The boiler proper includes upper and lower banks of tubes 26 and 27 which are separated vertically for purposes which will be presently explained. The tubes of the upper bank 26 are connected with headers 28 and 29 and the tubes of the lower bank with headers 30 and 31. The high end headers 28 and 30 are connected together in the usual manner and are connected to the drum 11 by tubes 32. The low end headers 29 and 31 are connected together in the usual manner and are connected with the drum 11 by return pipes 33.

15 In the form shown the furnace is provided with two openings 34 and 35 for the burners (not shown) and the combustion chamber is divided into two compartments by my improved center or partition wall, although of course any desired 20 number of such walls may be used to divide the furnace into as many sections as desired.

The center or partition wall includes two sets of tubes 36 and 37, the tubes of each set being of sufficient size and suitably spaced to reduce the 25 temperature of the adjacent portions of the furnace to the desired degree. As shown, the tubes of the walls 36 and 37 are arranged sufficiently close to make substantially two water walls adapted to divide the furnace into two 30 separate chambers. However, if desired, refractory material 38 may be inserted in the space between these walls in order to entirely separate the adjacent portions of the furnace.

The upper ends of the tubes of the water wall 36 are connected with a header 39, and the lower ends are connected with a header 40. The upper ends of the tubes of the water wall 37 are likewise connected with a header 41 which is arranged adjacent to the header 39 and the lower 40 ends of these tubes are connected with a header 42. While I have shown two headers 39 and 41 it will be understood that the two rows of tubes of the water wall may if desired be connected with a single header at the top. The headers 39 and 41 are connected respectively to the drum 11 through suitable riser tubes 43 and 44. The upper ends of the tubes 43 and 44 are arranged adjacent to each other and extend through a suitable opening in the upper bank 26 of boiler 50 tubes. The lower ends of the tubes 43 and 44 however are spread apart or separated to provide an access passageway 45 above the headers 39 and 41 in order to provide access to the hand hole covers 46 along the top of the headers, for 55 cleaning and repair. This passageway may be enclosed by means of side plates or walls 47 and is provided at the end with necessary entrance doors 48. The header 40 is connected by means of a pipe 49 with the return pipe 23 and the header 60 42 is connected by a pipe 50 with the return pipe 24 in order to complete the circuits of the water through the center or partition walls 36 and 37.

As shown in Figure 4, the center or partition wall is made in two sections of different heights 65 in order to accommodate the same to the variation or pitch in the main banks of boiler tubes and so as to provide access to the top of the section at the low end of the boiler.

The water walls 36 and 37 as shown are substantially parallel and quite close together but in order to provide access to the headers 40 and 42 the tubes of the respective walls are bent so that they diverge and form a passageway or opening 51 between the headers. The center walls 70 75 36 and 37 are carried by a longitudinal beam 52

which is supported in any suitable manner, the tubes being provided with supporting fins or lugs 53 which are welded thereto and which rest on the beam.

The spreading of the tubes of the center water 5 walls provides sloping side walls for the ash discharge openings 54 and 55 which extend longitudinally of the furnace instead of transversely as in the usual construction. The opposite sloping side walls of these ash discharges are formed 10 by bending in the lower ends of the tubes of the side walls 7 and 8, thus providing V-shaped discharge openings across the bottom of the furnace. The tubes of the water walls 7 and 8 are also provided with lugs or fins 56 and 57 which are carried 15 on beams 58 and 59 which extend longitudinally of the furnace and are of substantially the same height as the beam 52. This provides for uniform expansion of the lower ends of the water walls for attachment to ash handling devices. 20

The ashes may be disposed of by any suitable form of ash removing apparatus as for instance an automatic sluicing system as indicated at 60 or a standard ash pocket 61 for hand disposal as also shown in Figure 1. The sides of the ash discharge portion of the furnace, as well as other parts of the apparatus, may be provided with any standard form of refractory or insulated type of setting as may be required.

In the particular embodiment of my invention 30 shown, the upper and lower banks of boiler tubes have been separated a sufficient distance to permit the installation of a superheater 62, which may be suitably connected to the drum in any desired manner. However, where a superheater 35 is not required less distance may be provided between the upper and lower banks or the boiler tubes may be combined in a single bank and merely sufficient space left at the center for the headers 39 and 41 and the other parts connected therewith and for the access passageway.

The operation of my improved apparatus will be readily apparent from the above description taken in connection with the drawings. When heat is supplied to the two sections of the furnace 45 by means of suitable burners, the center water wall 36 will cooperate with the water wall 7 in order to keep the temperature in the corresponding section reduced to the desired amount. In a like manner the water wall 38 will cooperate with 50 the side water wall 8 to control the temperature in the other section. It will be noted that each of the center water walls will substantially absorb its proportion of the radiant heat from its individual section and will protect the other wall 55 from being injuriously affected by the radiant heat from the burner in such section. The circulation through the boiler and other features of operation are sufficiently obvious so that further description does not appear necessary. 60

Any invention or subject matter herein shown or described but not claimed is not intended to be dedicated to the public, such matter being shown, described and claimed in my copending divisional application for Steam generators, Serial Number 65 53,880, filed December 11, 1935.

It will be noted that while I have shown a preferred form of my invention it may be embodied in various different types of furnaces and different kinds of boilers of either the cross drum type as 70 shown or the long drum type, or other types to which it may be applicable, and therefore I do not wish to be limited to the particular construction herein shown and described except as set forth in the following claims, in which I claim: 75

1. In an apparatus of the character set forth, the combination of a boiler having upper and lower banks of tubes and having a drum connected therewith, of a furnace having side water walls and having a partition formed of two adjacent water walls extending upwardly through the lower bank of tubes and terminating between the banks, headers for the upper and lower ends of said water walls, means connecting the headers with the drum and an enclosed access passageway above the upper headers to provide access thereto.

2. The combination with a boiler of the inclined horizontal tube type having a bank of tubes and having a drum connected with said tubes, of a furnace, means for dividing the furnace into zones, comprising two series of tubes arranged adjacent to each other, the tubes of one series being adapted to shield the tubes of the adjacent series, headers for the lower ends of each of the series, headers for the upper ends of each of the series located above the lower tubes of the boilers, pipes leading from said last named headers to the drum, the upper portions of the pipes being arranged adjacent to each other, and the lower portions of the pipes of the adjacent headers being spaced apart to provide a passageway and a lining for enclosing said passageway.

3. A furnace having a partition comprising two tubular water walls arranged adjacent to each other, headers connecting the lower ends of the tubes of the respective walls, the lower portions of the tubes being spread apart to provide access to the headers.

4. A furnace including a combustion chamber having side water walls each formed of a series of tubes and having a central partition formed of two adjacent water walls which divides the chamber into sections, the lower portions of the tubes of the water walls in each section of the furnace being converged to provide longitudinal ash discharges, the space between the lower por-

tions of the partition water walls also providing access to the headers at the lower ends of said walls.

5. A furnace having a combustion chamber divided into a plurality of sections for combustion zones, each section having tubular water walls on either side thereof and means for supporting each of said walls at a predetermined distance from the lower end thereof whereby the expansion and contraction of all of the walls below the supports will be substantially the same.

6. A furnace comprising a substantially rectangular combustion chamber divided into two longitudinal sections to provide separate combustion zones, tubular water walls on either side of each section, the lower ends of the tubes of each section converging and forming an ash discharge passageway, and means for supporting all of said tubes at substantially the same distance from the lower ends thereof.

7. In a steam generator, the combination of a boiler having upper and lower banks of tubes, a drum operatively connected with said tubes, a series of vertical tubes extending longitudinally of the boiler with their upper ends above the lower bank and their lower ends projecting downwardly to the bottom of the furnace, a header connecting the lower ends of the tubes of said series, a second header connecting the upper ends of said series, means for operatively connecting said headers with the drum, a second series of tubes arranged adjacent to the first series and substantially parallel thereto, the tubes of the second series being co-extensive with the tubes of the first series, a header for the lower ends of the tubes of the second series, a header for the upper ends of the tubes of the second series arranged in juxtaposition to the upper header of the first series and means for operatively connecting the headers of the second series with the drum.

ARTHUR E. DURAM.
